UNITED STATES PATENT OFFICE.

WILLIAM L. MILLER, OF ST. PAUL, MINNESOTA.

MACHINE FOR MAKING ELECTRICAL COILS.

Application filed November 7, 1923. Serial No. 673,273.

My invention relates to electrical coils and machine for making the same and has for its object to provide a coil adapted to be formed upon the interior of a tube or similar structure.

Another object of the invention resides in forming a coil having alternate layers of wire and tubing, the inner-most layer being formed on the interior of the tube.

Another object of the invention resides in providing tubes for electrical coils of laminated formation which may be built up to any desired thickness and may be constructed of any diameter or length required.

A still further object of the invention resides in the process of forming said coil and in providing a machine for constructing the same.

Other objects of the invention reside in the detailed construction of the machine for forming the coils.

Another object of the invention resides in providing means for forming upon a single machine coils of any diameter or length or of thickness of tube or core and of forming layers of wire upon the interior or exterior of said tube or of imbedding said layers of wire within the tube.

The full objects and advantages of my invention will be found in the detailed description thereof and are particularly pointed out in the claims:

In the drawings forming part of this specification:

Figure 1 is a plan view of the invention.

Figure 2 is a side elevational view of the device shown in Figure 1, illustrating a portion of the same in section.

Figure 3 is a sectional view of the forming drum of the invention.

Figure 4 is a longitudinal sectional view of a portion of one of the coils.

Figure 5 is a transverse sectional view of a portion of one of the coils.

My invention consists primarily in the forming of coils for electrical purposes especially adapted to use with radio apparatus. One of the primary features of the invention resides in providing a coil upon the interior of a tube as well as another coil upon the exterior of the said tube thereby reducing the expense of constructing the coils and simplifying the formation of the same.

In forming the coils, the innermost winding is wound upon a collapsible drum with

the required number of turns. A continuous strip of gummed paper or other suitable material having an adhesive applied to the same is then successively wrapped about the coil with the adhesive side adjacent to the coil so that the same adheres thereto. When sufficient convolutions of paper have been wrapped about the winding to form a tube of the required thickness, the second winding is placed upon the tube completing the coil. Upon collapsing the drum on which the coil is constructed, the entire coil may be completely removed therefrom with both the inner and outer coils securely attached to the tube proper. By employing this principle of forming coils upon either the inner or outer surface of a tubular core or of imbedding the layers of wire within the tubes coils may be made which can be used for variometers, variocouplers, audio or radio frequency transformers or in fact any type of inductance used in radio construction.

In the construction of electrical coils in accordance with my invention, the same are preferably constructed as follows: A layer of wire is first wound upon a collapsible drum and the ends of the same properly secured. A tube is then built upon the drum by applying to the top of the layer a band of tube stock which has been coated with a suitable adhesive. This tube stock is then wound upon the coil until the tube assumes the desired thickness. Another coil is then wound upon the exterior of the tube which completes one of the types of tubes which is adapted to be constructed in accordance with my invention. Such a tube is shown in detail in Figures 4 and 5 in which the first layer of wire of the coil, is indicated at 67, the tube at 68 and the second layer of wire at 69. If desired, a layer of tube material can first be wound upon the drum and the alternative layers of wire and tube stock placed upon the same so that any number of coils may be formed in alternate relation and imbedded within the coil. The number of different types of coils which can be made with my invention are innumerable. Of the said coils, coils with an air core between the windings may be mentioned. For use as a variocoupler such a coil would be constructed with the main coil or stationary coil wound upon the interior of the tube and with the rotary coil wound upon the exterior of its tube. In

multiple winding, coils of similar nature where the coupling is fixed, the coils may be constructed with the wire wound upon the interior of the larger core, and upon the exterior of the smaller core. The marginal portion of the smaller core could then be built up to the same diameter as the internal diameter of the larger core with narrow tube stock and the larger core slipped over the same. Such a coil heated to drive out the moisture could be hermetically sealed, if desired, to provide a moisture proof coil.

The machine for forming the coils is best illustrated in Figures 1 and 2. This machine comprises a base 10 upon which are mounted four standards 11, 12, 13 and 14 supporting the structure of the same. These standards are provided with uprights 15, 16, 17 and 18 and with feet 19 connected therewith by means of which said uprights may be attached to the base through screws 20.

The upper ends of the uprights 16 are formed with grooves 21 extending longitudinally along the same in which is positioned a shaft 22. The shaft 22 is threaded at its circular portion at 23 and has screwed upon it two nuts 24 and 25. Upon the said shaft adjacent the nuts are placed two vertically positioned plates 26 and 27 which are formed with a portion of the same struck out from the metal thereof as indicated at 28 whereby the same are arranged in yieldable relation thereto. Between the plates 26 and 27 is positioned a roll of material 31 from which the tubes of my improved coils are constructed, which roll is held in frictional engagement with the said plates by means of the nuts 24 and 25 which engage the spring portions 28 of the same. For holding the plates 26 and 27 from rotation, a bar shown in dotted lines at 29 is employed which extends across the upright 16 of standards 12 and 14. The plates 26 and 27 are formed with notches 30 engaging this bar whereby the same may be positioned in any relation upon the same.

By this arrangement, the roll of tube material 31 may be placed in any position along the shaft or spindle 22 and any tension may be secured upon the same.

For guiding the tube material as the same leaves the roll 31, I employ two rollers 32 and 133 which are provided with trunnions 33 journaled in the upright 15 of standards 11 and 14. These rollers are positioned one above the other as shown and the stock passes as indicated at 34 over the roller 32 and beneath the roller 133. For guiding the stock over said rollers, I employ a number of adjustable flanges 35 which may be secured in place upon the said roller at any locality thereon by means of set screws 36.

Between the two standards 11 and 12 are positioned two troughs 37 and 38 in which

are rotatably mounted two moistening or adhesive applying rollers 39 and 40. When a gummed tape is used for forming the tubes, water is placed in the troughs 37 and 38 as indicated at 14 to a height sufficient to come in contact with the lower surface of the said rollers. If a blank stock is used, a liquid adhesive is placed in said troughs. It will be noted that the lower portion of the rollers 43 and 133 is below the upper portions of the rollers 39 and 40 so that the stock, upon leaving the roller 133, comes in contact with the upper portions of the rollers 39 and 40. At the same elevation as the roller 133 is positioned a similar roller 42 which is journaled to the upright of standard 12 and below which the stock 34 passes previous to being formed into tubes. At the upper end of the uprights 17 of standards 12 and 13 is journaled a drum A in a manner to be presently described, on which is formed the coils previously referred to, which will be more fully explained in detail. The stock of the tube forming material 34 as before stated, passes over the roller 33 successively over both of the rollers 40 and 39 and then beneath the roller 42 and up to the drum A where the tubes are formed by rotating the said drum as will be presently explained. For increasing the surface of contact of the stock as it passes over the rollers 39 and 40, a roller 43 is employed which is similar in construction to the rollers 32 and 133 and which is formed with trunnions 33 similar to those of the rollers 32 and 133. By means of these trunnions, the roller 43 is journaled in two arms 44 which are in turn pivoted at 45 to the uprights 15 of standards 11 and 14. When the said arms are swung downwardly, as shown in full lines in Figure 2, the roller 43 will hold the stock of material in contact with the moistening or adhesive applying rollers 39 and 40 which causes the stock to become moistened or coated with adhesive as the same passes through the device.

For supporting the roller 43 in its operative position, I provide two stops 46 which are formed integral with the upright 15 and which are adapted to engage below the arms 44 to prevent the roller 43 from dropping downwardly below the desired point. For preventing the roller 43 from being raised when tension is placed upon the stock of material 34, a coil spring 47 is used which is seated against a bar 48 extending across the two uprights 15 of standards 11 and 14 at one end and at its other end in a socket 49 attached to the end of a screw 50 mounted in an upright 51 which is attached to a similar bar shown in dotted lines in Figure 2 at 52 secured to the arms 44. By this means, the roller 43 is normally held to cause the stock of material, as it passes over the rollers 39 and 40, to become properly

moistened or coated with adhesive as required.

The construction of the tube forming device A is best illustrated in Figures 2 and 3. This device consists of a tube or drum portion 52 which is slit at 53 along an element thereof. At the ends of the drum 52 are attached semi-circular blocks 54 and 55, which, when the drum 52 is in its normal position, remain spaced from one another. By bringing these blocks together, the drum 52 may be collapsed sufficiently to remove the tube and coil constructed thereon therefrom, as will presently be described. Along the axis of the drum 52, I position a square shaft 56 which fits into notches 57 and 58 formed in the blocks 54 and 55. When the said blocks are held together, the same are caused to clamp upon the shaft 56 to center the said drum upon the said shaft and hold the same from movement thereon. For latching the blocks 54 and 55 together, I employ a hook 64 which is pivoted at 65 to the block 55 and which engages at its hooked end a pin 59 formed on the end of the block 54. By this means the blocks and drum may be securely attached to the shaft 56 as before specified. The shaft 56, as before stated, is square throughout its length excepting at two portions thereof indicated at 60 and 61 where the same is formed of cylindrical construction to provide portions whereby the said shaft may be journaled. This shaft is journaled in the uprights 17 of standards 12 and 13 as best shown in Figure 2. The bearings for this shaft are partly formed in the said upright 17 and are further formed by means of caps 61 which are hingedly connected at 62 to said upright 17. These caps may be closed down upon the shaft 56 to properly journal the same or the said caps may be swung out of the way to permit the complete removal of the drum and shaft from the device when the occasion arises. For holding the said caps in place, I employ hooks 63 pivoted to said caps which are adapted to engage pins 66 in the said uprights.

In forming the tubes of the invention, the tube stock, indicated at 34, is attached to the periphery of the drum 52 and the same wound upon the tube by turning the shaft 56 by means of a handle 67 secured to the exterior thereof. When sufficient amount of tube stock has been wound upon the drum, the same is cut off and the end sealed upon the tube. After removing the drum and shaft from the machine by raising the caps 61, the latch 64 may be disengaged, permitting the entire drum to be removed from the machine after which the same may be collapsed to remove the tube formed thereon from the same.

For guiding the stock 34 at the point where the same is wound upon the drum A, I provide a square bar 68 which is secured to

the upper ends of the upright 18 of standards 12 and 13. Upon this bar are slidably mounted two wing-shaped guides 69 and 70 which are attached to bosses 71 having set screws 72 therein by means of which said guides may be adjustably positioned wherever required upon said bar or rod 68. In this manner, the stock upon leaving the drum A may be guided so that a tube having smooth ends may be provided thereby requiring a minimum amount of finishing upon the end of the tube.

For attaching the paper to the drum 52 when the tube is commenced, I provide a device shown in detail in Figure 3. This device consists of a T-shaped member 72 which is positioned within the interior of the drum 52. This member is formed with a head portion 73 lying adjacent the under-edge of the drum at the opening 53 therein and with another head portion 74 adapted to rest against the shaft 56. The said member is provided with a stem portion 76 by means of which the same is pivoted to the end blocks 55. At the extreme end of the head portion 73 are provided a number of sharp points 77 which project through the opening 53 where the same are adapted to engage the tube stock and hold the same in place as the drum is rotated. When it is desired, to hold the device from use, the same is swung on the pivot 76 until it takes the position shown in dotted lines at 78 where a corner of the shaft 56 engages a notch 79 formed in member 72 holding it as required.

After the tube stock has been severed upon the completion of a tube, the end of the stock remaining attached to the tube is wound up and attached to the tube proper. The stock remaining attached to the roll 31 is then drawn back over the roller 43 and attached to a number of points 80 formed upon a bar 81 secured to the arms 44. The said arms 44 of the roller 43 attached thereto may then be swung upwardly upon the shafts 45 until they reach the position shown in dotted lines in Figure 2. This structure may then be held in this position by means of a finger 181 pivoted to the stop 46, which finger is adapted to engage against a lug 82 formed on the arm 44. When so positioned, it will be noted that the stock 34 is held upwardly and away from both of the rollers 39 and 40. The reason for this is obvious. If the stock were allowed to rest upon the said rollers, the same would soon adhere thereto causing the machine to become gummed up and rendered inoperable.

For winding the wire upon the drum A, the following structure is employed: Issuing outwardly from the uprights 17 are provided two brackets 83 which have rigidly secured to the same at the extreme end thereof a transversely positioned rod 84. Upon this rod is slidably and rotatably mounted a pul-

- ley 85 which serves to feed the wire upon the drum as the drum is rotated. In addition to the pulley 85, a yoked member 86 is also employed which is slidably mounted upon the said rod 84 and which is adapted to slide the pulley 85 back and forth as the said member is reciprocated. This member has a finger 87 attached to the same, which finger is shown in dotted lines in Figure 2 and is formed with a single thread 88 adapted to engage a threaded spindle 89 rotatably mounted in the arms 83. As this spindle is turned, finger 87 is caused to advance along the same and the pulley 85 moved therewith.
- For driving the spindle 89, a gear 90 is employed which is directly attached to the shaft 56. This gear meshes with another gear 91 having a trunnion 92 formed thereon by means of which said gear is directly journaled in the arm 83. The spindle 89 as will be noted in Figure 2, has a squared end 93 which is adapted to fit into a corresponding socket 94 formed in the trunnion 92 of gear 91. This spindle is further provided with a bearing portion 95 of a diameter larger than the diameter of the said spindle so that the same can be withdrawn through the arm 96 from the device without disturbing the gear 91. A keeper 97 pivotally secured to the arm 96 serves to hold the spindle 89 in place during the operation of the device. By swinging this keeper away from the end 95 of pivot 89, the said shaft may be removed, as before stated.
- In using the device, the member 86 is swung outwardly as shown in dotted lines in Figure 2 and the said member slid along until the pulley 85 occupies the position to which it is desired to commence the coil. The same is then swung upwardly until the single thread 88 engages the threads on the spindle 89. A keeper 98 pivoted to the underside of the finger 87 is then swung beneath the spindle 89 so that the thread 88 is held in engagement with the threads of the said spindle. By rotating the crank 67, the drum 52 is caused to rotate, which, in turn, rotates the spindle 89 and causes the wire to be fed along the drum as the same is wound thereon. It can readily be understood that different pitches of thread can be formed upon the spindle 89 so that the different sizes of wire may be equally as well wound upon the drum. It is therefore merely necessary to have one spindle, such as shown at 89, for each size of wire and to interchange the same when it is desired to wind the different sizes of wire upon the machine.
- For holding the wire spool, the structure shown in Figure 2 is employed. A spool 99 containing the wire to be wound upon the drum 52 is positioned upon a spindle 100 of the same construction as the spindle 22 on which the roll 31 is mounted. This spindle is adapted to be slid into two slots 101 where the same becomes firmly lodged. Upon the said spindle are screwed two thumb screws 102 similar to the thumb screws 25 which engage two plates 103 bearing against the flanges of the spool 99 and frictionally engaging the same to provide the required tension. These plates are held from movement by a bar 104 extending across the uprights 17 in the same manner as the bar 29. With this construction, the spool 99 may be positioned in any place upon the spool 100 and the tension of the wire leaving the same may be regulated as required.
- In using the device, the following procedure is adopted: Member 86 is first swung downwardly to occupy the position shown in dotted lines in Figure 2. If it is desired to provide a coil which is wholly imbedded within the tube, the stock 34 is run beneath the drum 52 and secured to the point 77 previously referred to. By turning the handle 67 clockwise, the same is wound upon the drum 52 with the gummed side on the exterior. This process is continued until a tube of the required thickness is provided. The stock is then cut, the free end of the same attached to the prongs 80 and the arms 44 resting as shown in dotted lines in Figure 2. The pulley 85 is then slid along to the required position upon the tube thus formed and the wire from the spool 99 drawn up and passed over the said pulley and secured to the tube thus formed in any suitable manner as by piercing a hole through the said tube at the slot 53 in drum 52 and extending the free end of the wire into the said drum. The handle 67 is then rotated until the required number of turns of wire have been wound upon the tube. The wire is then cut and the free end secured to the tube in the same manner. By now releasing the stock from the points 80 and cutting off the dried portions of it, the same may be attached to the coil or reel of wire thus wound upon the tube and the remainder of the tube finished, the stock being positioned between the guides 69 and 70 and attached to the rearward side of the drum where the same may be wound upon the drum by turning the handle 67 in a counter clockwise direction until the tube assumes the required thickness. After the stock has been severed, another layer of wire may be wound upon the coil and, if desired, a third tube placed over the same. If desired, the layer of wire may be wound directly upon the drum and the tube stock directly wound upon the said layer of wire. When a coil has been completed, the caps 61 are released and thrown back which permits the shaft 56 and drum 52 attached thereto to be removed from the machine. Then the said drum may be collapsed by releasing the hooks 64 and withdrawing the shaft 56, to-

- gether with the gear, 90, and crank handle 67, attached thereto from said drum. This permits the sections of the drum to be forced toward one another releasing the coil which 5 may be easily slid off from the same. It can readily be seen that many different types of electrical coils may be formed on the machine employing one or more layers of wire supported upon or within a tube. By using 10 one tube with a coil within the same and another tube with a coil upon the exterior of the same, variable inductances can be constructed having a very close coupling.
- The advantages of my invention are manifest. A machine is provided by means of which all varieties of coils, such as used in radio work, may be readily constructed without the expense of carrying a large stock of tubes upon which to build the same. At the 15 same time, primary and secondary coils may be wound one within another employing but a single tube thereby greatly reducing the cost of the same. If desired, the coils may be wholly imbedded within the tube material 20 so that the same are not exposed to view and are protected from injury or breakage. The machine for constructing the coils is of such a nature that the coils may be accurately and quickly made. Tubes of any desired 25 thickness can be readily made and by interchanging of drums, the diameter of the tube can be adjusted at will. If desired, uncoated or gummed paper or other suitable 30 tube stock may be employed with the machine to construct the tubes of any material desired. The tube stock is fed along 35 throughout the machine and is guided by the guides and adjustable flanges on the rollers so that the same becomes evenly wound 40 upon the drum, thereby forming a smooth uniform tube. The wire is automatically fed along the tube so that a smooth, uniform coil is produced and by interchanging the 45 said spindles any size of wire may be equally as well wound upon the tube, which may be 50 tight wound or spaced. The machine is so constructed that alternate layers of wire and tube stock may be wound upon the drum, thereby permitting coils of any design to be 55 constructed.

In accordance with the patent statutes, I have described the principles of operation of my invention, together with the apparatus which I now consider to represent the best embodiment thereof, but I desire to have it understood that the construction shown is only illustrative and that the invention can be carried out by other means and applied to uses other than those above set forth within the scope of the following claims.

I claim:

1. A process of constructing electrical coils consisting of winding a coil upon a collapsible drum, of applying adhesive to

a continuous strip of tube stock, of wrapping said tube stock with the adhesive side in contact with said coil about said coil and drum until the desired thickness of tube stock is secured and of collapsing said drum 10 and removing the same from said coil.

2. A process of constructing electrical coils consisting of winding a winding upon a collapsible drum, of applying adhesive to a continuous strip of tube stock, of wrapping 15 said tube stock the adhesive side in contact with said coil about said coil and drum until the desired thickness of tube stock is secured, of winding a second winding upon the exterior of said tube and of collapsing 20 said drum and removing the same from the said coil.

3. A machine for forming electrical coils comprising a winding drum, a pair of adhesive applying devices, means for feeding 25 tube stock across said adhesive devices, means for depressing said tube stock between said devices for increasing the surfaces of contact therefor and means for applying tension to said tube stock.

4. A machine for forming electrical coils comprising a winding drum, a pair of adhesive applying devices, means for feeding tube stock across said adhesive applying devices, means for depressing said tube stock 30 between said devices for increasing the surface of contact thereof, means for securing the free end of said tube stock to said depressing means and means for supporting said depressing means in elevated relation 35 to said adhesive applying means to bring said tube stock away from said adhesive applying means.

5. A device for forming electrical coils comprising a support, a pair of adhesive 40 applying devices, means for feeding tube stock across said adhesive applying devices, a pair of arms hingedly connected to said support, a roller pivoted to said arms and adapted to depress said tube stock between 45 said adhesive applying devices to increase the surface of contact therewith, means formed on said arms for holding the extreme end of said tube stock when the same has 50 been severed, resilient means for holding 55 said roller in engaging position and means for holding said arms in elevated position to bring said tube stock away from said adhesive applying devices after the end of the 60 tube stock has been secured to said holding 65 means.

6. A machine for forming electrical coils comprising a collapsible drum, means for supporting said drum whereby said drum may be removed in its entirety, means for 70 feeding wire upon said drum, means for feeding tube stock upon said drum and means for causing said drum to rotate.

7. A machine for forming electrical coils comprising a pair of reel standards, a 75

pair of forward standards positioned in spaced relation to said reel standards, a shaft for supporting a roll of tube stock, mounted on said reel standards, means for applying tension to said tube stock, a pair of adhesive applying devices positioned between said pairs of standards, a plurality of rollers secured to said standards for guiding the tube stock over said adhesive applying devices, means for holding said tube stock in engagement therewith, a drum rotatably mounted in said forward standards and guides for guiding said tube stock from said rollers to said drum.

15 8. A process of constructing coils consisting of winding a coil upon a collapsible drum, of supplying adhesive tube stock, of

wrapping said tube stock in contact with said coil about said coil and drum until the desired thickness of tube stock is obtained, 20 and of collapsing said drum and removing the same from said coil.

9. A process of constructing electrical coils consisting of winding a coil upon a collapsible drum, of wrapping adhesive tube 25 stock with the adhesive side in contact with said coil about the same and wrapping the tube stock there about until the desired thickness of tube stock is secured, of winding a second coil upon the exterior of said tube and of collapsing said drum and removing the same from said coil. 30

WILLIAM L. MILLER,
